UNITED STATES PATENT OFFICE.

EARL L. MINCH, OF BELLEVUE, OHIO.

DESIGN FOR A SILVERWARE-STAND.

49,477.

Specification for Design.

Patented Aug. 1, 1916.

Application filed June 7, 1916. Serial No. 102,229. Term of patent 7 years.

To all whom it may concern:

Be it known that I, EARL L. MINCH, a citizen of the United States, residing at Bellevue, in the county of Huron and State of Ohio, have invented a new, original, and ornamental Design for a Silverware-Stand, of which the following is a specification, reference being had to the accompanying drawing, forming part thereof.

The figure is a perspective view of a silverware stand, showing my new design.

I claim:

The ornamental design for a silverware stand as shown.

In testimony whereof I have affixed my signature in presence of two witnesses.

EARL L. MINCH.

Witnesses:

ALLAN G. AIGLER,
W. A. HAMMOND.
